DRAINBOARD TRAY

Meyer Steinberg, Woodmere, N.Y. (½ Ideal Rubber Products Co., 273-299 Van Sinderen Ave., Brooklyn, N.Y.)

Filed Jan. 2, 1963, Ser. No. 73,028

Term of patent 14 years

(Cl. D9—6)

Fig. 1.

Fig. 2.

Fig. 3.

FIG. 4.FIG. 5.

FIG. 1 is a top perspective view of a drainboard tray, embodying my new design;

FIG. 2 is a transverse cross-sectional view taken on the line 2—2 of FIG. 1;

FIG. 3 is a longitudinal cross-sectional view taken on the line 3—3 of FIG. 1;

FIG. 4 is a bottom perspective view thereof; and

FIG. 5 is a side elevational view thereof taken from the left side of FIG. 1.

I claim:

The ornamental design for a drainboard tray, substantially as shown.
